[57] CLAIM

The ornamental design for a tamper-proof fastening device for tags and the like, substantially as shown and described.

DESCRIPTION

FIG. 1 is an exploded perspective view of a tamper-proof fastening device for tags and the like showing my new design;

FIG. 2 is a front elevational view thereof;

FIG. 3 is a side elevational view taken from the right of FIG. 1;

FIG. 4 is a top plan view thereof; and

FIG. 5 is a rear elevational view thereof.
